UNITED STATES PATENT OFFICE

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA

BOX

Application filed November 5, 1930. Serial No. 493,500.

My invention relates to the art of making boxes, containers or the like, hereinafter generically termed "boxes", which particularly are wrapped with a label, or wrapper, 5 of paper or other suitable material.

In accordance with my invention, a box with walls of substantial thickness, for holding cigars or other goods, is formed by utilizing a wrapper to hold or to assist in holding 10 several box-forming components of heavy cardboard or the like in box-forming position; preferably, the wrapper is applied to the components substantially immediately 15 after they have been arranged in box-forming relation and more specifically, components forming the end walls of the box are brought into adhesive, abutting engagement, without overlap, with the edges of the side walls and box bottom, preferably 20 formed by a single component, and before the adhesive holding the components has set, a wrapper and preferably a tabbed wrapper is applied to cover the box formed by the 25 components and to supplement the union of the components; the tabbing, if utilized, overlying at least the vertical and horizontal corners of the box ends.

My invention resides in the box and methods of making it hereinafter described and 30 claimed.

For an understanding of my invention reference is made to the accompanying drawing in which in perspective:

Fig. 1 illustrates the several box forming 35 components before assembly.

Fig. 1a illustrates a modified type of box components.

Fig. 2 shows the components of Fig. 1 moved into box forming position.

Fig. 2a shows the assembled components 40 for a modified form of box.

Fig. 3 illustrates a wrapper.

Fig. 4 discloses the box assembly of Fig. 2 superimposed upon the wrapper of Fig. 3.

Fig. 5, represents a box cover at an intermediate stage of its formation.

Fig. 6 is a hinge strip.

Fig. 7 illustrates the completed, wrapped box, with cover attached thereto.

50 Referring to Fig. 1 the main box com-

ponent A is bent along the scoring X to form the side wall S and the box bottom B. The component before bending is rectangular and may be cut from heavy sheet cardboard, or the like, or as described and claimed in my 55 co-pending application Serial No. 485,631, filed October 1, 1930, the main component A may be severed from laminated cardboard strip (Fig. 1a) formed from two or more thinner strips, removed, for example, from 60 rolls. Or insofar as certain aspects of my invention are concerned, the component A may be of wood, or any of the well-known synthetic woods or wood substitutes and be formed of one piece of material or several 65 pieces suitably united.

Adhesive is applied as indicated at y, to the thick end edges of the main component A, and with the side walls and bottom in the position shown in Fig. 1, the end wall components 70 E, of material which may be the same as, or different from, that of the main component A is brought into engagement with the vertical and horizontal end edges of the main component A, the partially completed box assuming 75 the appearance shown in Fig. 2.

These end wall components may also be cut from card-board strip, preferably laminated (Fig. 1) as described and claimed in my aforesaid application. If desired both the 80 main component A and the end components E may be lined or covered on the side adapted to form the box interior, concurrently with formation of the laminated strips from which they are cut, also as described in my aforesaid 85 application.

While this assembling may be performed manually, preferably, it is done by mechanism similar to that shown in copending 90 Rider application Serial No. 460,859, filed June 13, 1930, in which end wall components are cut and transported to form block structure against the ends of which they are held by suitable means, and upon descent of the 95 form block, the end wall components are brought into box forming position with respect to another component corresponding to component A which has been fed into the path of movement of the form block. During 100 continued operation of the machine, a wrap-

per, or sheet material, which preferably is attached to the main component before feeding to the form block, and which is prepared, or coated concurrently with preparation of the box components, is manipulated to unite the components permanently in box forming position, as hereinafter more specifically described.

- As an alternative the box assembly shown in Fig. 2 may be superimposed upon a freshly prepared wrapper, such as the wrapper W of Fig. 3, with the box bottom B in register with and adhesively engaging the wrapper panel b. The assembly comprising the box and partially applied wrapper as shown in Fig. 4 may then be transported to for example, a form block of a box machine, the adhesive at y assisting in maintaining the box components A, E, E, in proper position. For example, the assembly may be fed to the form block by transfer mechanism such as shown in accompanying Rider and Bailey application Serial No. 490,400, filed October 22, 1930.
- During the box wrapping operation, which may be performed by box machine generally of the type shown in Federwitz Patent 1,541,255, and more specifically in the aforesaid Rider, and Rider et al applications, the side panels s, s of the wrapper W are applied to the side panels S, S of the main component A. Thereafter, the corner flaps f, of the wrapper are folded into engagement with the end wall component E overlying the box end corners formed by the adhesively attached ends of the end components and the vertical and horizontal end edges of main component A. The covering of the exterior of the box is continued by the folding of the end panels e of the wrapper W upwardly into engagement with the end wall components E. As the end walls project above the tops of the side walls of the box specifically illustrated, the end panels e of the wrapper are suitably longer than the side panels. To complete the wrapping, the marginal portions m of the end and side wall panels o, are turned over the top edges of the box and down into engagement with the box interior.
- Whereas in my prior application Serial No. 88,231, filed February 15, 1926, the box components are held in box forming relation solely by the wrapper, in accordance with the present invention, which is specifically directed to the formation of heavy boxes, or boxes having one or more thick walls, the wrapper in holding the box components in position supplements adhesive or the like directly attaching them but insufficient of itself to insure a union of sufficient strength.
- Preferably, the wrapper W is provided with tabs t adapted to reinforce the end corners of the box formed by the end wall components E and the ends of the main component A. Or tabs may be applied to the box

assembly without a wrapper, in which case the tabs are applied to the main component A, to project in part beyond the end edges thereof so that during the box forming operation the projecting tab portions are folded into engagement with the end components to unite the components in box forming position and to reinforce the corners formed thereby, the tab as applied assuming substantially the same position as when applied with a wrapper.

Particularly when the boxes are not of the drop-lid type, that is having higher end walls than side walls, the adhesive may be applied to the side and bottom edges of the end components E', instead of to the end edges of the main component A, and the end wall components E are then embraced by the main component A, with the bottom edge of the end components resting upon the upper surface of the box bottom B as shown in Fig. 2a.

The box lid L, Fig. 5, may also be formed of heavy carboard, or the like, the length of the cover being substantially equal, when the box is of the drop-lid type, to the distance between the projecting box ends. A label l, or other sheet covering material, may be applied to the lid. In the example shown, the label completely covers the top surfaces of the cover and the projecting portions p are turned over the edges of the box and into engagement with the limited area of the inside or under surface.

The lid is or may be attached to the completed box by hinge strip h, Fig. 6, which is coated with adhesive on one side and applied in part to the cover and to the rear side wall of the box. Ordinarily, this hinge strip may directly engage the covering material or wrapper for the box and for the lid L. Both the wrapper W and the lid label or cover l may have printed thereon edging strips, and panels grained to imitate wood, in addition to printed matter for trade-mark or advertising purposes.

The box, when made entirely of carboard, particularly laminated carboard, as above described, compares favorably with wooden boxes in strength, durability, appearance, etc., and is much cheaper and simpler to manufacture.

It is characteristic of my preferred method of producing boxes, that substantially immediately after the box components are assembled as in Fig. 2, they are wrapped to form a box, as distinguished from methods in which wrappers are applied to previously formed boxes. More fully stated, in accordance with my preferred method, complete, wrapped boxes are individually and successively produced whereas in accordance with known methods a quantity of unwrapped, previously formed boxes are made and then wrappers are applied to them.

What I claim is:

1. The method of forming a cardboard

cigar box, which comprises bending a box component of substantial thickness in position to form the box bottom and sides, effecting adhesive engagement between each of the 5 thick end edges of said component and the box-interior face of an end wall component, and adhesively applying sheet-material to overlite the end corners of the box.

2. The method of making a box, which 10 comprises attaching box components in box-forming position by adhesive, concurrently coating a wrapper with adhesive, and before setting of the adhesive on the wrapper and the adhesive attaching said components, applying a wrapper to cover the box and to 15 assist in holding said components in box-forming position.

3. The method of making a box, which 20 comprises attaching box components in box-forming position by adhesive, concurrently therewith coating tab structure and a wrapper with adhesive, and before setting of the adhesive on the tabs, wrapper and between the box components, the step of applying the 25 tab structure and wrapper to said box with the tab structure overlying corners of the box formed by components attached to each other by adhesive.

4. The method of forming a cardboard 30 cigar box, which comprises bending a cardboard box component of substantial thickness to form the box bottom and sides, applying adhesive to the thick end edges of said component, transporting cardboard box ends 35 into engagement with said end edges of said first component, coating a wrapper with adhesive, and before setting of the adhesive attaching said components, applying the freshly 40 coated wrapper to cover the box and to assist in holding said components thereof in box-forming position.

5. The method of forming a cardboard cigar box, which comprises bending a cardboard box component of substantial thickness 45 to form the box bottom and sides, applying adhesive to the thick end edges of said component, transporting cardboard box ends into engagement with said end edges of said first component, coating a wrapper with adhesive, 50 before setting of the adhesive attaching said components, applying the freshly coated wrapper to cover the box and to assist in holding said components thereof in box-forming position and attaching a cover to 55 said box by a hinge strip adhesively applied in part to said cover and in part to said wrapper.

6. The method of forming a cardboard cigar box, which comprises scoring and bending laminated cardboard box structure to 60 form a box bottom and a pair of vertical walls, transporting separate box components of laminated cardboard and adapted to form a second pair of vertical walls into box-forming position with respect to said structure,

attaching said components and said structure while in said position by adhesive applied to the end edges of the laminations of at least one of said components, and before setting of the adhesive, adhesively applying a wrapper to supplement said adhesive in uniting said components and said structure. 70

7. A box comprising separate component of thick box-forming material held in abutting relation by adhesive between thick edges of the ends of one of said components and the box-interior face of another of said components, and sheet material overlapping the corner formed by said adhesively engaging components and adhesively attached to said components adjacent said corner. 80

8. A box comprising a component of thick box-forming material adapted to form the box bottom and side walls, end wall components secured to said first component by adhesive on the thick end edges thereof, and a wrapper adhesively applied to said box and supplementing said adhesive in holding said components in box-forming position. 85

9. A drop-lid box comprising a component of thick box-forming material adapted to form the box bottom and side walls, end wall components secured to said first component by adhesive on the thick end edges thereof and projecting above the top of said side walls, and a wrapper adhesively applied to said box and having portions connecting the end wall components to said first component and supplementing said adhesive in maintaining said components in box-forming position. 95

10. A box comprising a component of heavy cardboard adapted to form one or more box walls, a separate component attached to said first component by adhesive on the thick edge of one of said first components, and a wrapper adhesively applied to said box supplementing said adhesive in holding said components in box-forming position. 105

11. A drop-lid cigar box comprising a component of heavy cardboard adapted to form the box bottom and side walls, and wall components attached by adhesive to the thick end edges of said first components and extending above the sides thereof, and a wrapper having panels of unequal height for covering the side walls of the first component and the end wall components of greater height and turn-in portions for overlying corners of the box formed by components directly attached by adhesive. 115

12. A drop-lid cigar box comprising a component of heavy cardboard adapted to form the box bottom and side walls, end wall components attached by adhesive to the thick end edges of said first components and extending above the sides thereof, a wrapper having panels of unequal height for covering the side walls of the first component and the end wall components of greater height and turn-in 130

portions for overlying corners of the box formed by components directly attached by adhesive, a box cover of heavy cardboard adapted to rest on the top edges of said side walls, a wrapper adhesively applied thereto, and a hinge strip therefor adhesively applied to the cover wrapper and said box wrapper.

13. The method of forming a composite box which comprises effecting adhesive abutting engagement between the end edge of a component forming one wall of a box and the box interior face of a component forming an adjacent wall, and before setting of the adhesive, adhesively applying sheet material to connect the box exterior faces of said components and to overlie the corner formed thereby.

14. The method of forming a composite box which comprises effecting adhesive abutting engagement between the end edges of the side walls and bottom and the box-interior face of a component forming an end wall, and adhesively applying sheet material to connect the box exterior faces of said components and to overlie the end corners of the box formed thereby.

15. The method of forming a composite box which comprises effecting adhesive abutting engagement between the end and bottom edges of a component forming the box end with the box-interior faces of the box-bottom and side walls, and adhesively applying sheet material to connect the box exterior faces of the box end, bottom and sides and to overlie the corners formed by the joinder thereof.

JOHN S. STOKES.
